UNITED STATES PATENT OFFICE.

GEORGE COMPTON, OF NEW HAVEN, CONNECTICUT, ASSIGNOR TO THE RATTAN MFG. CO., OF NEW HAVEN, CONNECTICUT, A CORPORATION.

BABY CARRIAGE.

Application filed November 23, 1926. Serial No. 150,246.

This invention relates to improvement in baby carriages, and particularly to an adjustable back-attachment for baby carriages. A stylish form of baby carriage at present 5 has a deep body,—that is, the sides extend upward into the plane of the front and back. It is desirable that carriages of this type should be provided with an adjustable back, so as to permit a child to recline, and the 10 object of this invention is to provide a baby carriage with an adjustable back, with means for locking the back in various positions of adjustment, and the invention consists in the construction as hereinafter described and 15 particularly recited in the claims.

In the accompanying drawings:

Fig. 1 is a side view of a baby carriage constructed in accordance with my invention, showing the adjustable back in its lowered position;

Fig. 2 is a plan view of the frame of the adjustable back in its lowered position;

Fig. 3 is a longitudinal sectional view of the same; and

Fig. 4 is a perspective view of the keeper-plate detached.

In carrying out my invention, the back 5 of the body 6 is cut away to leave clearance for an adjustable frame 7. This frame is 30 hinged to a transverse brace 8 extending across the back. In the frame and so as to be housed thereby is a longitudinally-arranged rod 9 extending upward through the upper edge of the adjustable frame and provided at its outer end with a knob or handle

10. Upon the rod and tending to force it downward is a spring 11. This rod extends through the lower frame-piece 12 of the adjustable back and projects beyond it into engagement with a curved keeper-plate 13, which is provided with perforations 14, more or less in number and herein shown as three, this keeper-plate being secured to the transverse-brace 8, which is formed with 45 a notch 15 to give clearance for the lower end of the rod 9. The adjustable back will be upholstered to correspond with the upholstery on the inside of the carriage-body, and between the adjustable back and the body is a hood 16 of flexible material which will fold inward when the adjustable back is raised, but will cover the space between the adjustable back and the carriage-body, so as to form a protection for the face of the 55 child.

When the back is in its raised position, the end of the rod 9 will engage with a hole 14 in the keeper-plate, and so hold the adjustable back flush with the back of the carriage-body. To lower the adjustable back, the 60 rod 9 is drawn outward so as to lift the end of the rod out of engagement with the hole 14, and then the adjustable portion of the back is moved outward to the desired extent and the rod released so as to engage 65 with one of the openings 14. Thus, the adjustable back may be locked in its raised or full open position, or at one or more intermediate points.

It will be understood that the outer face 70 of the adjustable back is finished to correspond with the finish of the carriage-body, so that, when in its raised position, it is inconspicuous, and when dropped forms a convenient head-rest for a child.

I claim:

1. The combination with a baby-carriage body cut away at its back, of a transverse brace secured to the inside of the back at the lower edge of the cut-away portion and 80 formed with a notch, an adjustable back-frame fitting in the cut-away portion and hinged to said brace, a longitudinally-movable rod housed in said back-frame, a keeper fixed to said brace and extending inward and 85 upward through said notch and formed with a plurality of openings with either of which the lower end of said rod may engage, and a spring on said rod tending to force it downward.

2. The combination with a baby-carriage body cut away at its back, of a transverse brace secured to the inside of the back at the lower edge of the cut-away portion and 95 formed with a notch, an adjustable back-frame fitting in the cut-away portion and hinged to said brace, a longitudinally-movable rod housed in said back-frame, a keeper fixed to said brace and extending inward and upward through said notch and 100 formed with a plurality of openings with either of which the lower end of said rod may engage, a spring on said rod tending to force it downward, and a flexible hood connected with the adjustable frame and 105 with the back of the body.

In testimony whereof, I have signed this specification.

GEORGE COMPTON.
